UNITED STATES PATENT OFFICE.

ARTHUR M. EVENSON, OF WESTBY, WISCONSIN.

CHAIN-FASTENER.

1,332,719.

Specification of Letters Patent.

Patented Mar. 2, 1920.

Application filed July 7, 1919. Serial No. 308,958.

To all whom it may concern:

Be it known that I, ARTHUR M. EVENSON, a citizen of the United States, residing at Westby, in the county of Vernon and State 5 of Wisconsin, have invented certain new and useful Improvements in Chain-Fasteners, of which the following is a specification.

My invention relates to new and useful improvements in means for drawing the free 10 ends of a chain or like toward each other and locking them in a tightened position, but more particularly for tightening and locking anti-skid chains about automobile tires.

15 An important object of the invention is to provide a device which is capable of drawing the free ends of a chain toward each other, then coöperating with the chain for locking the ends of the same in their 20 stretched or tightened position.

Another object of my invention is to provide a device having its various parts so constructed and adapted for coöperation that the various parts will be arranged in compact relation either when the device is in use 25 or not in use.

A further object of my invention is to provide a device of the above mentioned character which may be permanently connected to one anti-skid chain, and thereby 30 dismiss all possibility of its loss when in use.

A still further object of my invention is to provide a device which is strong, durable, inexpensive to manufacture, and efficient in 35 practice.

Other objects and advantages of the invention will become apparent during the course of the following description.

In the accompanying drawings forming a 40 part of the description and wherein like numerals are employed to designate like parts throughout the same,

Figure 1 is a side elevation of the invention applied to a chain.

45 Fig. 2 is a top plan of the same.

Fig. 3 is a side elevation of the invention in an unlocked position, and

Fig. 4 is an end view of the invention in a locked position.

50 In the drawings, wherein for the purpose of illustration is shown a preferred embodiment of my invention, the numeral 5 designates the handle or lever which is substantially S-shaped in configuration. The end 6 of this lever is adapted to interlockingly engage with the free end of a chain 7 or the

like, and the end 6 is curved laterally of the lever in hook shaped fashion as clearly shown at 8 in Fig. 4 of the drawings. The opposite end of the lever 5 is pivotally connected within bifurcated end 8' of a bowed member 9 by means of a rivet, the heads of which rivet are flush with the opposite sides of the bowed member for a purpose which will appear later. The snap hook 11 is provided upon the opposite end of the bowed member by curving this end hook-fashion and providing the usual flat spring 12 for bridging the space between the free end of the hook and the shank thereof.

70 The other free end of the chain 7 has its end link 13 pivotally connected to the joined ends 14 of a slightly arcuated U-shaped yoke 15 through the medium of a rivet 16 or the like. The opposite ends of the arms 75 comprising the yoke are pivotally connected to opposite sides of the lever 5, a substantial distance from the pivot connection of the bowed member 9 with the free end of the lever 5, by means of a rivet 17 or the like, 80 whereby swinging movement of the lever will cause movement of the yoke 15. As more clearly shown in Fig. 2 of the drawing, spacing collars 18 are provided upon the shank of the rivet 17 and interposed between 85 the lever 5 and the arms of the yoke 15.

When an anti-skid chain is being positioned upon an automobile tire, the tightener or fastener assumes the position as shown in Fig. 3 of the drawing. By gripping the end 6 of the lever 5 and swinging the lever toward the snap hook 11 of the bowed member 9, it will be seen that the yoke member 15 will be carried therewith, which action will of course cause the end 90 of the chain which is connected to the yoke to be moved toward the opposite end of the chain which is engaged with the snap hook. During this operation, it will also be manifest that the bowed member 9 will 95 sometimes be moved together with the free end of the chain to which it is connected, toward the opposite end of the chain which is connected to the yoke, thereby tightening the chain to the desired tension in a minimum amount of time.

100 After the lever 5 has been swung to its closed position, as illustrated in Figs. 1 and 2 of the drawing, it will be seen that the bifurcated end 8' of the bowed member 110 together with the end of the lever 5 which is pivotally connected thereto, will have

swung up between the two arms comprising the yoke 15. Inasmuch as the bifurcation extends substantially half the length of the bowed member, the curved end of the lever 5 to which the yoke is connected, will be slightly received in the bifurcation, which arrangement permits the curved end 6 of the lever to slightly surround and be arranged in close proximity to the hooked end 10 of the snap hook 11.

After the lever 5 has been swung to the position illustrated in Fig. 1, the laterally extending hooked end 8 of the lever extends under and snugly engages one arm of the 15 end link of the free end of the chain 7. When the device is in this position, it will be seen that the anti-skid chain has been effectively tightened about the tire, and the chain will remain in a securely locked position 20 inasmuch as the hooked end 8 of the lever cannot become accidentally disengaged from the chain. It will also be manifest that the tightener and fastener by the construction of its various parts provides a 25 highly compact arrangement.

If it is desired to remove the chain from the tire, the end link of the free end of the chain is simply swung slightly out of alignment with the fastener so that the hooked end 30 8 of the lever may pass between the opposite arms of the link and be swung toward the opposite end of the chain to loosen the same.

The foregoing description and the draw-

ings have reference to what may be considered the preferred, or approved, form of invention. It is to be understood that I may make such changes in construction and arrangement and combination of parts, materials, dimensions, etc., as may prove expedient and fall within the scope of the appended claim.

Having thus fully described my invention, what I claim as new and desire to secure by Letters Patent, is:

45

In a chain tightener and fastener, the combination of an S-shaped lever with a bowed member having a bifurcated end, a pivot provided for connecting the bifurcated end of said bowed member with one free end of said lever, a yoke member having its arm pivotally connected to opposite sides of said lever adjacent the pivotal connection of the bowed member therewith, a snap hook provided upon the free end of 55 said bowed member, said lever having its free end extended laterally of its body portion so as to penetrate the opening of a link and engage one side thereof so as to prevent accidental displacement, said link 60 also engaging said snap hook.

In testimony whereof I affix my signature in presence of two witnesses.

ARTHUR M. EVENSON.
